DUPLICATING MACHINE WITH AUTOMATIC CONTROLS

Richard E. Cragg, Wilmette, and Walter A. Raczyński, Park Ridge, Ill., assignors, by mesne assignments, to Ditto, Incorporated, Chicago, Ill., a corporation of Delaware

Filed Sept. 8, 1961, Ser. No. 136,767
12 Claims. (Cl. 101—144)

This invention relates in general to lithographic duplicating machines and, more particularly, to a system for automatically controlling the operation of offset lithographic duplicating machines. An offset lithographic machine of the kind considered herein is disclosed in the United States Patent No. 2,753,795, issued to H. F. Bruns on July 10, 1956.

An offset duplicating machine is a complicated mechanical structure, and successful and efficient operation of the machine correspondingly complicated and demanding. By way of explanation, each time that the offset machine is used for purposes of producing a plurality of copies from a master sheet it is necessary to perform three distinct operational steps. These three major operational steps may be identified as the pre-printing operation, the printing operation and the post-printing operation.

In the pre-printing operation the imaged lithographic master is clamped into position on the duplicating machine and the master is moistened in preparation for the printing operation. In the printing operation ink and moisture are applied to the master and paper is fed to the machine in cycles to reproduce copy. In the post-printing operation the duplicator is cleaned and dried and restored to its initial condition in readiness for the next duplicating run.

For effective and efficient use of the offset duplicator it is necessary that these three major operational steps be carried out with care and attention. However, this care and attention is not always available in the office environment because of the inavailability of skilled operator personnel. Where the requisite skill is lacking the copy quality level is diminished, and the cost per sheet of produced copy is high because of spoilage and inefficient use of the machine. Inefficient use of the machine is perhaps enhanced by the fact that many operations thereon are manually performed requiring stopping of the machine and placing increased reliance upon the manipulative skills of the operator.

The present invention has been directed to an improved programming unit for offset duplicator machines so as to prevent mistakes and errors in the use of the machine by minimizing the factor of operator skills whereby the use of the offset duplicator machine is rendered more effective and efficient.

This invention lends itself to being incorporated as an integral portion of a duplicating machine, or it may be adapted as an attachment to a duplicating machine of a character disclosed in United States Patent No. 2,753,795, issued to H. F. Bruns on July 10, 1956.

Offset duplicators of the prior art such as the type disclosed in United States Patent No. 2,916,988, issued to R. E. Cragg on December 15, 1959, automatically control the moisture system, the ink system, and the blanket roll and paper feed mechanisms, so that they become operative at preselected times, the time sequence being dependent on the number of revolutions of the main cylinder. Such a system is semi-automatic in that it carries out essentially only the printing operation and is shut off after a preselected number of copies have been made. The operators of such offset duplicators are, however, required to carry out a great number of manual operations while running the machine.

2

Offset duplicators of the prior art including the duplicators mentioned above have several disadvantages. As an instance, during the printing operation there may be a demand for overfeeding additional sheets, which sheets

5 are not to be included in the preselected copy count of the machine but are to be considered as an overrun. In duplicator machines of the prior art there is no facility for overrun because the machine counts each copy and turns off after the preselected copy count is reached. A further disadvantage is that in a printing run there may be a requirement for overfeeding narrow stock, such as punched cards for data processing. In such a situation machines of the prior art must be turned off and the feed system manually adjusted to handle the narrow stock and upon completion of the overfeeding a second adjustment will have to be made in order to adapt the machine to resume feeding the regular sized stock.

Another example of a disadvantage in machines of the prior art is that the excess ink on the surface of the lithographic master is removed after the printing cycle has been completed by feeding extra sheets of paper to the duplicator without feeding ink to the lithographic master thereby depleting the image on the master. This is a waste of paper and an unnecessary expense particularly on short runs.

20 A further example of a disadvantage of machines of the prior art, is that at the end of the duplicating cycle the ink image on the blanket roll is manually removed in preparation for processing of the next lithographic master 25 by washing the blanket roll with a suitable solvent. The applied solvent requires some time to evaporate from the blanket roll surface and consequently there is an extended delay prior to the running of the next duplicating operation.

30 With these few examples in mind it is apparent that there exists considerable number of obstacles preventing efficient use of presently available offset duplicating machines and it is the general object of the present invention to overcome these obstacles.

35 The principal object of this invention is to provide a new and improved programming system for a lithographic duplicating machine so that skilled duplicating machine technicians are not required for the operation thereof and high quality printing can be turned out rapidly and economically.

40 A more specific object of the invention is to provide a new and improved programming system for an offset duplicating machine that will, upon initiation, automatically and consecutively operate the machine through its 45 pre-printing operational step, through its printing operational step and finally through its post-printing operational step.

45 One of the features of this invention is the provision 50 of a mechanism which is adapted automatically to operate and to release the clamping arrangement by means of which the primary master and any overlay master that may be carried thereon are, respectively, retained to the machines as soon as the duplicating cycle is initiated and released from the machine as soon as the duplicating cycle is completed.

55 Another feature of this invention is the provision of a mechanism that is automatically controlled after the lithographic master has been clamped on the main cylinder for pre-moistening the master sheet.

60 Another feature of this invention is the provision of a selectively controlled mechanism which upon operation 65 renders the copy count device of the programming system inoperative thereby permitting an overrun of additional copies without disturbing the basic programming of the duplicating machine.

70 Another feature of this invention is the provision of

a supplemental feed tray mechanism which when introduced into the machine interrupts the normal feed and the pre-set cycle programmer to print the additional number of copies furnished by the supplemental feed mechanism and which when the last sheet in the tray feeds, normal feeding is restored and the programmer reverts to complete the pre-set cycle.

Another feature of this invention is the provision of a control which automatically adjusts the feeding mechanism when narrow stock is introduced by means of an overfeed tray.

Another feature of this invention is the provision of a clean-up attachment operative at the end of each printing operational step for cleaning the residual ink from the blanket roll.

Another feature of this invention is the provision of a drive mechanism that maintains the blanket roll in contact with the lithographic master at the end of the printing operational step so that the lithographic master may also be cleaned of its inked image from the clean-up attachment. Thus, at the conclusion of the printing operation, the lithographic master, as well as the blanket roll, is cleaned of excess ink thereby permitting early storage and filing of the lithographic master.

Another feature of this invention is the provision of an attachment for removing residual solvent from the blanket roll during the heretofore described cleaning operation, so that the blanket roll is quickly readied to accept a new image for the subsequent duplicating cycle.

Another feature of this invention is the provision of an automatic ejection mechanism for ejecting the lithographic master into a copy receiving tray, after the completion of the cleaning operation.

Another feature of this invention is the provision of a control operated upon ejection of the master into the receiving tray for feeding a blank sheet of protective paper from the paper feed tray through the duplicating machine and into the receiving tray on top of the ejected lithographic master to eliminate ink staining and aid in drying the lithographic master.

Further objects and features of the invention pertain to the particular structures and arrangements whereby the outlined objects are achieved and the listed features are rendered effective.

The invention, both as to its structure and method of operation will be understood from the following description and from an examination of the accompanying drawings which illustrate an embodiment of the invention and in which similar numerals refer to similar parts throughout the drawings.

In the drawings:

FIGURE 1 is a side elevational view of a duplicating machine which does not comprise the present invention but illustrates a machine of a kind adapted to be operated by the arrangement of the present invention;

FIGURE 2 is a view in elevation of the opposite side of the machine shown in FIGURE 1;

FIGURE 3 is a front view in elevation of a control panel of the programming arrangement of the present invention showing selector switches effective for carrying out control functions on an offset duplicating machine;

FIGURE 4 is a diagrammatic view of one form of the stepping switches which may be utilized as components of the control box shown in FIGURE 3;

FIGURE 5 is a circuit diagram of the pre-printing portion of the programming control circuit of a duplicating machine embodying the features of the invention;

FIGURE 6a is another circuit diagram of a portion of the electrical control system of a duplicating machine embodying the features of the invention with the appropriate connection to leads from other circuit diagrams being shown by corresponding Roman numerals;

FIGURE 17b is a side elevation of a portion of a machine embodying the invention and further illustrates the paper ejector rake interlock mechanism.

GENERAL ORGANIZATION

The duplicating machine illustrated in the drawings just described closely resembles the duplicating machine disclosed in the previously identified United States Patents Nos. 2,753,795 and 2,916,988. Accordingly, only the elements of the present machine which are operatively associated with this invention will be described in detail in this application.

A duplicating machine of the kind adapted to be operated by the arrangement of the present invention is illustrated in FIGURES 1 and 2 and is comprised of a pair of side plates 10 and 12, which are secured in spaced relation by a plurality of tie rods (not shown) which support various sets of instrumentalities. FIGURE 1 of the drawings illustrates the main cylinder 14 of the duplicating machine in dotted lines mounted for rotation between the side plates 10 and 12. The main cylinder 14 comprises a plate segment and an impression segment. The plate segment is adapted to hold lithographic master plates in a manner generally described and shown in the above mentioned United States Patent No. 2,753,795. The impression segment is adapted to have the sheets of blank paper successively fed through the duplicator, clamped thereon, and rotated therewith, so as to have the desired printed image offset thereon from a rubber blanket roll during the operation of the machine.

The blanket roll which has a rubber surface is journaled between side plates 10 and 12 and is adapted to make rolling contact first with the moistened and inked lithographic master for the transfer of an inked image to the blanket roll and then with the paper on the impression segment of the main cylinder 14 to transfer the image to the copy paper. The blanket roll and the main cylinder 14 are inter-connected for rotation in a desired time relation by suitable gearing.

The machine is also provided with the conventional stack supporting feed tables, a feed separator and a sheet feeder together with a sheet feed roll assembly, the details of which are not shown here. A valve 39 is shown in FIGURE 1 which controls the operation of the sheet feeder, as will be more specifically described later. An ink applying assembly is also provided, the shaft 20 of the ink feed roll being shown in FIGURE 1 along with the shaft 22 of the ink form roll. Both of these rolls are capable of movement into and out of operative position as will be later described. A moisture supply means and a plate moistener assembly are also provided, the moistener feed roll shaft 24 being shown in FIGURE 1 along with the moisture form roll shaft 26.

This duplicating machine shown in FIGURES 1 and 2 has an electric motor serving as the prime mover which drives the various components of the machine and, in addition, operates a combined compressor-vacuum pump of conventional design which is incorporated into a pneumatic system which serves to operate certain components in the machine.

The machine also incorporates an automatic throw-out mechanism operating in proper time and sequence in conjunction with the sheet handling mechanism. Such a mechanism is adapted to be actuated by the interruption of the feeding of sheets in the machine and thereupon renders several sets of mechanisms in the machine inoperative, thereby preventing excessive build-up of ink and moisture on the lithographic master and blanket roll. This throw-out mechanism is described in detail in United States Patent No. 2,727,461, issued on December 20, 1955 to Herbert F. Bruns.

Incorporated in the throw-out mechanism is a means for independently regulating the pressure between the blanket roll and the plate segment of the main cylinder 14 and the blanket roll and the impression segment of the main cylinder 14. This permits the machine to automatically handle lithographic masters of various thicknesses, and likewise, is self-adjusting to handle copy paper sheets of various thicknesses. A lithographic duplicating machine of the character described herein may have a control panel at the front thereof in accordance with previously identified Patent No. 2,753,795 disposed between the lower ends of the side plates, upon which may be mounted all of the control switches for the various mechanisms in the machine.

FIGURE 3 of the drawings illustrates the control panel utilized in this embodiment of the invention with essentially all the requisite switches and dials required for setting up a program for automatically duplicating copies by an offset lithographic duplicator in accordance with the invention. Other portions of the duplicating machine will be described by referring to their functions.

Initially a lithographic master is prepared for the duplicator by typing, writing, drawing or by any other known process and the operator mounts the master on the main cylinder 14 of the duplicator machine.

AUTOMATIC CONTROL OF THE PRE-PRINTING OPERATION ACCORDING TO THIS INVENTION

Lithographic Master Jaw Clamps

Referring to FIGURES 15 and 16 there is illustrated the automatic lithographic master jaw clamp opening system and the lithographic master ejection system. Duplicator jaw clamps 520 and 521 are shown positioned

on the main cylinder 14 and in the open position. As will be seen, jaw clamps 520 and 521 are automatically opened at the conclusion of each duplicating cycle. Jaw clamps 520 and 521 are utilized to position both a primary lithographic master and a secondary lithographic master. The secondary lithographic master is optional and is provided in order that variable information may be added to or deleted from the primary lithographic master. Thus provision is made to overlay the primary lithographic master with a secondary lithographic master which contains variable information, so that in combination, they will duplicate the desired constant data and the variable data onto provided copy sheets.

Clamp relay 400, illustrated in FIGURE 9, when energized energizes clamp electro-magnets 527 and 528 shown in FIGURE 15 permitting the proper sequential ejection of the primary and secondary lithographic masters at the conclusion of the duplicating cycle. Clamp electro-magnets 527 and 528 and their associated mechanisms are secured to the side plate of the duplicating machine in any convenient manner. The secondary or upper master is ejected by lifting action of cam 524 to open the variable jaw 518 of jaw clamp 521. Thereafter the primary lithographic master is ejected by the opening of jaw 517 of jaw clamp 520 due to the lifting action of cam 523. The operation of the clamps 520 and 521 may be controlled so as to be individually opened or may open simultaneously.

Thus, as the operator starts a duplicating cycle the jaws of jaw clamps 520 and 521 are in an open position as will be more fully explained later. The initial manual operation of opening the jaws of the jaw clamps 520 and 521 has been eliminated.

The duplicator is readied for activation by closing power switch 125 illustrated in FIGURE 6a. The closing of switch 125 energizes rectifier 127 thereby providing direct current to the various relays, and magnets of the duplicator.

The operator inserts, for example, both the primary and secondary lithographic masters into the jaws 517 and 518 of the opened jaw clamps 520 and 521, respectively, and activates push button switch 401 conveniently positioned on the machine. Push button switch 401 is diagrammatically illustrated in FIGURE 9 but is not otherwise illustrated in the drawings and can, for example, be mounted on the control panel illustrated in FIGURE 3. As will be seen later, if relay 400 is energized at this time the opening of switch 401 de-energizes relay 400 thereby de-energizing electro-magnets 528 and 527 as can be seen in FIGURE 9. Referring to FIGURES 15 and 16 it can be seen that the de-energizing of electro-magnets 527 and 528 enables the right angle arms 531 and 532 of the lifting cams 523 and 524 to be pulled downwardly by the biasing springs 530 and 529, respectively. Movement of the lifting cams 524 and 523 enables the biasing springs 526 and 525 of the connecting arms 534 and 533, respectively, to rotate the clamp jaws 517 and 518 into their closed clamping position. Therefore at this time the primary lithographic master and the secondary lithographic master are firmly held in position on the main cylinder 14.

PRE-MOISTENING OF THE LITHOGRAPHIC MASTER

The pre-moistening mechanism 402 is illustrated in FIGURE 12 and comprises an operating handle 403 rigidly attached to shaft 404 for pivotal movement therewith. Shaft 404 may be securely fixed with relation to main cylinder 14 by any convenient means. Attached to shaft 404 is a spring 40 affixed to shaft 404 as shown and a conveniently placed stop 405-A positioned on the duplicator as required. Also rigidly attached to shaft 404 for movement therewith are arms 408-A to which is attached the moisture applicator 408. As can be seen in FIGURE 12 the pre-moisture mechanism 402 is

positioned adjacent the main cylinder 14 and is biased in a near vertical position in which position the pre-moisture mechanism 402 is inoperative. Immediately after the primary lithographic master and the secondary lithographic master are clamped in position on the main cylinder 14 the pre-moistening mechanism handle 403 is moved by the operator in a clockwise direction as seen in FIGURE 12. The applicator 408 which is made of a sponge material has been in contact with a fountain or moisture reservoir (not shown). As the handle 403 approaches a near horizontal position, as seen in FIGURE 12, latch 406 engages pawl 407 and latch 406 rotates partially around pawl 407 in a clockwise direction as viewed in FIGURE 12 to hold the pre-moistening mechanism 402 in the operative position in contact with the exposed lithographic masters. Push button start switch 128, shown mounted in the handle 403, is manually activated at the conclusion of the manual movement of the pre-moistening mechanism 402 thereby energizing stepping switch IV coil 100 from ground through push button 128, closed contacts 535, and the coil 100 to minus 90 volts as seen in FIGURE 5. In the initial or home position of stepping switch IV contacts 535 and contact 414 of stepping switch IV are closed and open, respectively. In any other position of stepping switch IV contact 535 and contact 414 are open and closed, respectively. Alternately, push button start switch 128 may be mounted in the main control panel as illustrated in FIGURE 3. Activation of push button start switch 128 and consequently stepping switch coil 100 causes wipers 409, 410, 411, 412 and 501 of stepping switch IV to advance one step, thereby energizing the duplicator. The movement of wiper 409 energizes motor relay 120 from ground, through wiper 409 of stepping switch IV, the plurality of connected contacts of stepping switch V associated with wiper 409 through the coil of relay 120 to minus 90 volts, thereby closing contact 121 of relay 120 to complete a circuit path to motor 129 whereby motor 129 is energized.

With the motor 129 operating, the main cylinder 14 now rotates, thereby causing the lithographic masters to contact the moisture applicator 408. The moisture applicator 408 will continue to contact the surface of the lithographic master with each revolution of the main cylinder 14 of the duplicator thereby pre-moistening the lithographic masters. Stepping switch IV and consequently wipers 409, 410, 411, 412 and 501 will be advanced one step responsive to each revolution of the main cylinder by pulses which are delivered to coil 100 of stepping switch IV from ground, through wiper 409 and its associated contacts of stepping switch IV, contact 413 of relay 220 illustrated in FIGURE 6b, contact 110 illustrated in FIGURE 7 which closes and opens with each revolution of the main cylinder 14 by the action of cam 111 attached to the main cylinder 14, through contacts 415 of stepping switch V operated by cam 477 attached to stepping switch V, contact 416 of relay 190 illustrated in FIGURE 6b, through coil 100 to minus 90 volts. Stepping switch IV will advance until wiper 409 reaches the position 430 of the stepping switch IV as will be seen. Contact 415 of stepping switch V will be closed only in the home position of stepping switch V. Otherwise contact 478 of stepping switch V will be closed. When wiper 412 has been advanced along with wipers 409, 410, 411 and 501 of stepping switch IV to the point at which the pre-moistening switch or etch switch control 417 illustrated in FIGURES 3 and 5, has been set, the wipers will home to position 418 by current coming from ground through wiper 412, switch 417, interrupter contact 107 and coil 100 of stepping switch IV to ground. The pre-moistening device or etching device 402 is then rendered inoperative, as will be explained hereinafter.

Referring to FIGURES 5, 6a, 6b and 12 it can be seen that etching relay 419 is energized from ground, through wiper 412 and contact 418 of stepping switch IV through

the coil of relay 419 to minus 90 volts. In response to the energization of relay 419 etching electro-magnet 420 is energized from ground through contact 421 of relay 419. The energization of etching electro-magnet 420 pulls interponent 422 against its biasing spring 423 thereby laterally moving interponent 422 to the right as seen in FIGURE 12 into the path of the vertical movement of cam follower arm 424. The cam follower arm 424 may be attached to the duplicator for pivotable movement as desired and convenient. Thereafter cam follower 424 acting through interponent 422 lifts latch 406, rotating latch 406 in a counter-clockwise direction as seen in FIGURE 12. As can be seen in FIGURE 12, the cam follower arm 424 is attached to roller 424A which normally rides on the cam surface 413A and when riding on cam surface 413A, the cam follower arm 424 will not engage interponent 422. When roller 424A rides on surface 413B, however, cam follower arm 424 pivots in a vertical direction engaging interponent 422, thereby causing the rotation and consequent disengagement of latch 406 from pawl 407. The biasing spring 405 thereafter urges mechanism 402 into its inoperative position wherein applicator 408 is in contact with a reservoir (not shown).

In order to provide a means for adjusting the pressure that the applicator 408 will apply to the surface of the lithographic masters, arm 546, spring 547 and the adjusting screw 608 are arranged as shown in FIGURE 12. The screw 608 is adjustably affixed to the arm 546 by means of internal threads (not shown) provided in the arm 546. The screw 608 is adjusted such that the cam follower arm 434 will engage the screw 608 whenever the cam roller 424A is riding on surface 413B thus pushing the entire assembly including the applicator 408 away from the surface of the lithographic master. The spring 547 serves to return the entire assembly to its normal position. Therefore it can be seen that the applicator will somewhat oscillate over the surface of the lithographic masters so as to more adequately wet the surface of the lithographic masters.

Thus, in the foregoing description, the operation of pre-moistening the surface of the lithographic masters is automatically performed so that the lithographic surface is now ready to be exposed to the ink form roller so that the grease receptive image will be inked for printing and the non-image area will remain hydrophylic and continue to receive moisture. However, moisture will now be supplied from the moisture form roller of the moistening system.

If the pre-moistening application is to be omitted or is not necessary, the pre-moistening mechanism 402 may remain in its inoperative position. The pre-moistening or etch switch 417 may be set to "0" causing the wipers of stepping switch IV to proceed directly to contact 412 of stepping switch IV upon the operator pushing the start button 128.

AUTOMATIC CONTROL OF THE PRINTING OPERATION ACCORDING TO THIS INVENTION

The printing phase of the duplicating cycle may be defined for the purpose of this invention, as including that portion of the cycle which commences with the application of moisture by the moisture form roll (not shown) to the lithographic master surface and concludes when the moisture system ceases to act upon the lithographic master thereby including the paper feed step and the like.

The control of that portion of the printing operation dealing with the moisture system and the ink system, which are brought into operating sequence and are automatically programmed is disclosed in previously identified United States Patent No. 2,916,988 and is incorporated herein by reference. Accordingly, the improvements of this invention which deal with the printing phase of the duplicating cycle will now be described over and beyond the automated control of the moisture system and the ink

system of the above identified invention. For the purposes of continuity certain aspects of the portion of the printing operation which deal with the control of the moisture system and the ink system will be discussed.

Accordingly, and referring to FIGURE 1, the moisture feed roll latch 30 is controlled by the electro-magnet 31. When the electro-magnet 31 is energized, arm 33 is free to pivot about stub 34, and when the electro-magnet 31 is deenergized arm 33 is inhibited from movement. The moisture feed roll shaft 24 is moved in and out of association with the moisture fountain in response to the energization of electro-magnet 31. The moisture form roll latch 35 is controlled by the energization of electro-magnet 32 and controls the movement of the moisture form roll shaft 26. The ink feed roll latch 36 controls the movement of the ink feed roll shaft 29 and is, in turn, controlled by the energization of electro-magnet 51. The position of the ink form roll shaft 22 is controlled by the ink form roll latch 37 and is, in turn, controlled by the energization of electro-magnet 52.

Similarly, the position of the valve arm 38 of the pneumatic paper feed control valve 39 is controlled by the latch 40, controlled in turn by the electro-magnet 91. The cam 41 normally moves the valve arm 38 to the open position during one revolution thereof and if the electro-magnet 91 is de-energized, the latch 40 is moved into a position such that it will block the return of the valve arm 38 to the closed position. On the other hand, when the electro-magnet 91 is energized the arm 38 will be free to close.

Refer now to the electrical circuit diagrams. The duplicating cycle as previously described has automatically progressed through the pre-printing cycle and the pre-moistening mechanism 402 is in its inoperative position. Water relay 130 has been energized inasmuch as wipers 410 of stepping switch IV have contacted contacts 418 of stepping switch IV as seen in FIGURE 5 and relay 130 is energized from ground, through wiper 410 and contacts 418 of stepping switch IV, through the coil of relay 130, to minus 90 volts. Water electro-magnet 31 is thereby energized from ground through contact 192 of relay 190, contact 131 of water relay 130, contact 425 of relay 486 and the coil of electro-magnet 31 to minus 90 volts. The electro-magnet 32 is also energized from ground through contact 132 of water relay 130 and the coil of electro-magnet 32 to minus 90 volts. Moisture will then be applied to the surface of the lithographic masters. As wipers 409, 410, 411, 412 and 502 of stepping switch IV continue to step over the previously described energizing path as a result of the rotation of the main cylinder 14, water relay 130 will remain energized through the aforesaid path through wiper 410 of stepping switch IV inasmuch as the remainder of the sequential switch contacts of stepping switch IV traversed by wiper 410 of stepping switch IV with the exception of home position 493 are bussed together.

Ink relay 150 becomes energized as soon as wiper 411 of stepping switch IV engages the switch contact connected to ink switch 117. Relay 150 is energized from ground through wiper 411, the preselected contact on switch 117, contact 429 of relay 494, and the coil of relay 150 to minus 90 volts. The operator presets ink switch 117 at the outset of the duplicating cycle as will be seen hereinafter and thereby determines the number of revolutions of the main cylinder 14 which contact the moisture form roller (not shown) before ink is fed to the cylinder 14. Ink relay 150 is held energized from ground, through contact 222 of relay 220, contact 153 of relay 150 and contact 429 of relay 494 and through the coil of relay 150 to minus 90 volts. Ink feed electro-magnet 51 thereafter becomes energized from ground, through contact 192 of relay 190, contacts 151 of relay 150, and the coil of the ink feed electro-magnet 51 to minus 90 volts. Ink form roll electromagnet 52 also becomes energized from ground, through contact 192 of relay 190,

contact 152 of relay 150, the coil of the ink form roll electro-magnet 52 to minus 90 volts. Ink is thereafter applied to the lithographic master.

To initially get a strong ink image on the lithographic master, the blanket roll is prevented from making contact with the lithographic master for several revolutions of the main cylinder 14 whereby the ink image builds up on the lithographic masters for several revolutions on the main cylinder 14. The blanket roll 13 is controlled through relay 170. Initially at the outset of the duplicating cycle the operator presets the blanket roll switch 118 thereby determining the number of revolutions that the lithographic masters receive ink before the ink image is transferred from the lithographic masters to blanket roll 13. Relay 170 is initially energized from ground, wiper 411 of stepping switch IV, through the preselected contact of stepping switch IV, the blanket roll switch 118, the coil of relay 170 to minus 90 volts. Relay 170 is thereafter energized from ground, through contacts 222 of relay 220, contacts 172 of relay 170 and the coil of relay 170 to minus 90 volts. Blanket roll electro-magnet 71 is energized when the relay 170 is energized, from ground, through contact 171 of relay 170, the coil of the blanket roll electro-magnet 71 to minus 90 volts.

The operator may wish to have the blanket roll 13 contact the lithographic master simultaneously with the first revolution of the main cylinder 14. This is advantageous when using lithographic masters which are clamped to the plate segment of the main cylinder 14 at one edge only. The blanket roll 13 will smooth out the lithographic master and cause the lithographic master to conform to the plate segment of the main cylinder 14. This is desirable because otherwise the unclamped edge might pick up ink from tie rods and ink rolls if it is flapping as it rotates rather than being secure to the plate segment surface.

Referring to FIGURE 5 and FIGURE 6b, the operator can first preset switch 118 to its first position such that position 418 of stepping switch IV is connected to the blanket roll switch 118. Next the operator can preset switch 417 to "0" causing wiper 411 of stepping switch IV to home rapidly to contact 418 of stepping switch IV thereby causing the blanket roll 13 to contact the lithographic master on the first revolution of the main cylinder 14. Contacts 418 and 515 are connected in parallel so that if the operator does not set the switch 417 to "0," the wiper 411 will not pass position 515 thereby giving relay 170 sufficient time to energize. This is of course optional. The stepping switch IV is rapidly homed to position 418 from position 515 from ground, the positions on stepping switch IV intermediate and including position 515 to, but excluding, position 418, the etch switch 417, the interrupter contact 107 and through the stepping coil 100 to minus 90 volts.

The paper feed system provided in this invention is capable of handling different size stock, as well as interrupting the count when over feeding extra sheets as will be seen hereinafter. At this time reference is made to the paper feed switch 119 which is preset by the operator and which is illustrated in FIGURES 3 and 5. Wipers 412, 409, 410 and 411 and 501 of stepping switch IV will be advanced with each rotation of the main cylinder 14 as previously described and upon reaching the preselected position on switch 119 all these wipers home to position 430 through a circuit from ground, through wiper 412 of stepping switch IV, the contacts of stepping switch IV connected to switch 119, switch 119, the interrupter contact 107 of the stepping switch IV, and through stepping coil 100 to minus 90 volts.

At position 430, the paper feed relay 190 is energized from ground, through wiper 412 and contact 430 of stepping switch IV, contact 431 of relay 170, the coil of relay 190 to minus 90 volts. It should be noted that contact 431 is closed at the time when the blanket roll relay 170

is energized. The paper feed magnet 91 is thereafter energized from ground, through contact 191 of relay 190, contact 432 associated with rake position cam 434, the coil of the electro-magnet 91 to minus 90 volts thereby commencing the feeding of paper. Also at this time contacts 416 of relay 190 are opened thereby preventing the stepping of stepping switch IV with each revolution of the duplicator main cylinder 14 over the previously described path.

PREVENTION OF JAMMING OF COPIES LEAVING THE DUPLICATOR

Referring to FIGURES 17a and 17b, rake 519 guides the ejection of copy paper into the receiving tray (not shown). If rake 519 is improperly positioned for any reason, a jam-up of copies leaving the duplicator usually occurs. To prevent this a normally closed micro-switch 432 and rake position cam 434 are added. Copy paper will not be fed to the duplicator unless the ejector rake 519 is in its proper position. Normally closed switch 432 is unaffected by the cam 434 when rake 519 is in its proper position. If rake 519 is in any other position cam 434 will depress the actuating arm of the switch 432 thereby opening the normally closed switch 432. Switch 432 is directly connected in the energizing path of the paper feed electromagnet 91 as can be seen in FIGURE 6b. Therefore switch 432 must be in a closed condition or electro-magnet 91 will not be energized and paper will not be fed to the duplicator.

COPY COUNT REGISTER

The recording of the exact count of the number of copies duplicated is accomplished in this invention during the printing operation by the unique use of stepping switches with the appropriate electrical circuitry shown in FIGURE 8. Prior art devices for recording the exact copy count in office type duplicators have been found unreliable due to wear of components and the complexity of design. The recording count device herein described goes well beyond the practical limitations required for office duplicating and in principle has no upper count limitation.

Referring to FIGURE 3, the operator selects the number of copies to be duplicated in any one duplicating cycle by setting the count switches at the appropriate position, such as units with dial switch 495, tens with dial switch 496 and hundreds with dial switch 497.

Referring to FIGURE 8, dial switches 495, 496 and 497, respectively, control stepping switches I, II and III, which in this example have the capability of counting 999 copies. By the use of suitable additional switches, it is possible to extend this count capacity to infinity. Each time the main cylinder 14 rotates while the paper feed relay 190 is energized, a copy sheet is fed into the lower feed rolls (not shown) of the duplicator. Referring to FIGURES 6a, 6b, 7 and 8, the sheet detector contact 201 alternately closes and opens in response to the feeding of copy paper thereby sending a pulse from ground, through contact 201, contact 441 of relay 586, switch 435, contacts 433 of relay 130 to the units switch stepping coil 436 to minus 90 volts. Hence, wipers 437, 438, 439 and 440 of stepping switch I are advanced one step and are subsequently advanced one step for each rotation of the main cylinder 14 when copy paper is being fed to the duplicator.

When the wipers 437, 438, 439 and 440 of stepping switch I reach contacts 442 of stepping switch I a current path is provided from ground, through wiper 409 of stepping switch IV at position 430, contacts 413 of relay 220, wiper 439 of stepping switch I, position nine of stepping switch I which is contact 442 of stepping switch I and the coil 443 of stepping switch II to minus 90 volts.

During the next revolution of the duplicator, which coincides with the tenth sheet of paper fed through the duplicator wiper 439 is stepped to the next contact posi-

tion 443 thereby de-energizing stepping coil 443 thereby advancing wipers 444, 445, 446 and 447 of stepping switch II one step. It is contemplated that stepping switches containing more than ten contact positions per cycle may be employed, in which case, the unused contacts must be bridged in order to establish a precise count in terms of units, tens and hundreds.

Thus far in the description of this improved count recording device, a total of ten sheets of paper have been fed and recorded with the wipers of stepping switch I having advanced to position 443. With the wipers at position 448, current will now flow from ground through wiper 409 and contact 430 of stepping switch IV, contact 413 of relay 220, wiper 439 and contact 443 of stepping switch I, interrupter contact 449 of stepping switch I to stepping coil 436 and minus 90 volts, thus homing the wipers 437, 438, 439 and 440 of stepping switch I beyond contact 448 to home position 450. It can now be seen that the tens stepping switch II steps one count when the units stepping switch I steps ten counts.

When wipers 444, 445, 446 and 447 of stepping switch II reach the ninth position or contact 451, which means that 99 sheets of paper have been fed through the duplicator, the hundreds stepping switch coil 452 becomes energized through wiper 446 in a manner similar to the foregoing description of the energization of coil 443 of stepping switch II from the units switch. Coil 452 of stepping switch III is energized from ground through wiper 409 and contact 430 of stepping switch IV, contacts 413 of relay 220, wiper 446 and contact 451 of stepping switch II and coil 452 of stepping switch III to minus 90 volts. At the 100th count, the wipers of stepping switch II are homed to their start position 450 by the action of the interrupter contact 453 of stepping switch II. Current flows from ground through wiper 409 and contact 430 of stepping switch IV, contact 413 of relay 220, wiper 446 of stepping switch II, the tenth contact of stepping switch II, interrupter contact 453 and coil 452 to minus 90 volts. Stepping coil 452 is de-energized when wiper 446 of stepping switch II is stepped to its tenth position indicating that one hundred counts have been received by the copy count register thereby advancing the wipers 454, 455, 456 and 457 of stepping switch III one step. Thus, in a similar manner it is contemplated that a thousands stepping switch or any number of like stepping switches could be added to extend the count to 9,999 or beyond.

As the paper feed continues, the count device responds in accordance with the preselected dial settings, which are made by the operator in programming the duplicating cycle. Therefore, wiper 454 of stepping switch III will advance to connect with hundreds switch 497; wiper 444 of stepping switch II will make contact with tens switch 496; and wiper 437 of stepping switch I will make contact with units switch 495.

After the count recording device carries out its assigned function as will be described, it is returned to the "0" position so that the succeeding portion of the duplicating cycle may, in turn, be automatically performed. At the instant the respective wipers of the count recording device stepping switches I, II and III reach their preset positions, relay 220 is energized in a manner to be discussed hereinafter. The energization of homing relay 220 occurs simultaneously with the energization of stepping coil 472 of stepping switch V shown in FIGURE 7, as will be explained and the printing instrumentalities which are no longer required are rendered inoperative.

When relay 220 is energized contact 222 of relay 220 opens, thereby de-energizing the ink relay 150 and the blanket roll relay 170 as can be readily seen in the drawings. The de-energization of the blanket roll relay 170, in turn, opens blanket relay contact 431, which in turn de-energizes the paper feed relay 190. Thus, in timed relation to the attainment of the preset count, the instrumentalities which are responsible for the actual printing

of copy are rendered inoperative and the paper feed functions are stopped.

It will be observed that each of the count recording switches which are stepping switches I, II and III will not attain their preset positions simultaneously, that is, the positions determined by the presetting of switches 495, 496 and 497. The hundreds switch, stepping switch III, will be the first in time to attain its final preset position with the tens stepping switch II, next and then the units stepping switch I in that order of time. After the stepping switches I, II and III have reached their preset positions, relay 220 is held in a condition of energization until each stepping switch of the copy count register attains its home position as will be more fully explained later. Relay 220 is held energized from ground, through the three parallel contacts 461, 462, 463 of stepping switches I, II and III, respectively, which are open only when the stepping switches I, II and III are in their home position, through contact 221 of relay 220, through the coil of relay 220 to minus 90 volts.

Assume that "377" copies are desired to be made and dial switches 497, 496 and 495 are set to "3," "7" and "7," respectively. When the sheet of paper corresponding to the preselected copy count "377" registered on switches 495, 496 and 497 is fed into the duplicator, the sheet detector contact 201 relays this signal to stepping coil 436 of stepping switch I from ground, contacts 201, contact 441 of relay 500, closed switch 435, contacts 433 of relay 130, the stepping coil 436 of stepping switch I to minus 90 volts thus energizing stepping coil 436 causing stepping switch wiper 437 to advance to position "7." Wiper 437 of stepping switch I contacts position "7" on switch 495 thereby completing a path from ground to wiper 444 of stepping switch II as readily seen in FIGURE 8.

Wiper 444 of stepping switch II has previously been stepped to its position "7" on switch 496 and wiper 454 of stepping switch III has previously been stepped to its position "3" on switch 497 as can be readily understood. Therefore, a path from ground to relay 220 exists from ground, through wiper 437 of stepping switch I, position "7" of switch 495, from switch 495 to wiper 444 of stepping switch II, through position "7" of switch 496, from switch 496 to wiper 454 of stepping switch III, through position "3" of switch 497, and from switch 497 to the coil of relay 220 to minus 90 volts. Relay 220 is thereby energized.

As previously stated when the homing relay 220 is energized, contact 222 of relay 220 opens de-energizing the ink relay 150 and the blanket roll relay 170. The de-energization of the blanket roll relay 170 opens contact 431 of blanket roll relay 170 thereby de-energizing the paper feed relay 190. Accordingly, the printing instrumentalities including the paper feed mechanism, the inking mechanism and the blanket roll are rendered inoperative.

Also when the homing relay 220 is energized contacts 468 of relay 220 are closed thereby causing the homing of stepping coil 452 of stepping switch III. The homing path occurs from ground, contacts 468 of relay 220, wiper 457 of stepping switch III, the plurality of bussed contacts of stepping switch III, the interrupter contact 469 of stepping switch III, and coil 452 of stepping switch III to minus 90 volts. Therefore, stepping switch III will open and close its own energizing path through interrupter contact 469 until wiper 457 resides on the home position or position 450 where the circuit path to ground is not present.

In like manner a homing circuit path to ground is provided for stepping coil 443 of stepping switch II from ground through contacts 223 of homing relay 220, through wiper 447 and the bussed contacts of stepping switch II, through interrupter contacts 453 and through coil 443 of stepping switch II to minus 90 volts. A homing circuit path to ground is provided for stepping coil 436 of step-

ping switch I from ground, wipers 469 of stepping switch I, contact 467 of relay 220, wiper 440 and the bussed contacts of stepping switch I, interrupter contact 449 and through coil 436 of stepping switch I to minus 90 volts. The homing of the stepping switches I, II and III returns the count recording device to the "0" position.

As previously stated, the foregoing steps occur only while the homing relay 220 is energized. The homing relay 220 is held energized as long as any of the contacts 461, 462 and 463 are closed, thereby keeping the homing relay energized from ground, through any of the contacts 461, 462 and 463, contacts 221 of relay 220, and through the coil of relay 220 to minus 90 volts. The stepping switch contacts 461, 462 and 463 of stepping switches I, II and III are closed in every position but the home position of their respective stepping switches. In the home position these contacts are open and the holding circuits to homing relay 220, previously described, are broken. Relay 220 therefore becomes de-energized when stepping switches I, II and III have been stepped to their home position.

USE OF OVERFEED TRAY

During the course of the printing operation feeding of additional sheets for the duplication of data from the lithographic master without disturbing or affecting the printing program and the original count setting may be required. Specifically, the operator may desire to overfeed a preselected additional number of sheets at any point of the duplication cycle which will not permanently affect the printing program in any manner.

To automatically provide for this contingency, a sensing device 503, shown in FIGURE 11, is positioned over the feed tray 522 of the duplicator. An overfeed tray 506 is inserted in the feed tray 522 and is positioned on the top surface of the blank sheets which are normally fed to the duplicator. The overfeed tray 506 raises the level of the extra sheets 507 to be overfed so that the extra sheets 507 are in surface contact with an overfeed sensing element 509. The sensing element 509 contacts the paper in the overfeed tray and is moved upwardly as seen in FIGURE 11 in solid lines thereby closing contact 499. Relay 500 is thereby energized from ground through contact 499. The energization of relay 500 opens contact 441 of relay 500 as shown in FIGURES 11 and 6a, suspending the copy count until all the blank sheets in the overfeed tray 506 have been fed into the duplicator. When the overfeed tray 506 has become depleted of sheets 507 to be overfed, the sensing element 509 is cleared as can be seen in dotted lines in FIGURE 11 and with the overfeed tray 506 still in position, regular stock is fed from the feed tray 522 permitting the interrupted program to continue.

As previously stated, when the sensing element 509 is in contact with the overfeed paper 507 in the overfeed tray 506, relay 500 is energized thereby opening contact 441 of relay 500. When contact 441 is open the circuit between the sheet detector switch 201 and stepping coil 436 of the units stepping switch I is opened. The opening of this circuit prevents the energization and de-energization of the stepping coil 436 of stepping switch I as the sheets are fed into the machine from the overfeed tray. Consequently, the units stepping switch is not advanced, and the feeding of paper from the overfeed tray may continue until the sensing element 509 is no longer in contact with the surface of any sheets 507 being overfed. Thus, when the overfeed tray 506 has been exhausted of the sheets to be overfed, the switch 499 opens de-energizing relay 500 so that contact 441 of relay 500 now closes thereby closing a circuit path between the sheet detector contact 201 and the stepping coil 436 of the units stepping switch I. Therefore, as soon as the feeding of paper from feed tray 522 begins coil 436 of stepping switch I is energized and de-energized as the sheets are fed into the duplicating machine thereby advancing the wipers of the

stepping switches I, II and III until they reach the pre-selected setting of the switches 495, 496 and 497.

It may be desired to overfeed paper or cards of narrow widths to the duplicator and not have them affect the set-up printing operations and also to do this without adjusting for the width of overfeed paper or cards. This may be accomplished by implementing the duplicator with a pair of suction feet one of which, suction foot 525, being illustrated in FIGURE 11.

The suction feet are positioned side by side and over the uppermost copy sheet. Due to the partial vacuum created in the vacuum system (not shown), the uppermost sheet will be lifted by the suction feet and presented to the duplicator. Therefore, if overfeed paper or cards of narrow stock are fed to the machine possibly only one suction foot would be positioned over the overfed paper or cards and therefore an effectual vacuum leak would occur in the system. Therefore, a feed control electro-magnetic air valve 511 is provided and connected to one of the suction feet and specifically suction foot 525.

The feed control electro-magnetic air valve 511 is illustrated in FIGURES 6a and 11 and as can be seen will be energized when relay 500 is energized and therefore will be energized when the overfeed tray is utilized in the duplicator. However, to insure that both suction feet may be utilized when the overfeed tray is being used the switch 513 illustrated in FIGURES 3 and 6a is provided. When switch 513 is in its "off" condition, switch 513 is open and it is not possible to shut off one of the vacuum feet. When switch 513 is in its "on" condition then the suction foot 525 will be shut off whenever the overfeed tray is used.

INTERRUPTION BY USE OF A MANUALLY OPERATED SWITCH

Flexibility is an important consideration in any automated offset duplicator. By a suitable switch arrangement provided for in this invention the preselected programming of the duplicating cycle is interrupted at any point in the cycle to duplicate any additional number of selected sheets without disturbing the subsequent programming of the duplicator. As shown in FIGURES 3 and 6b a switch 435 is provided in the circuit path between the sheet detector contact 201 and the stepping coil 436 of stepping switch I which breaks the circuit path from the sheet detector contact 201 to stepping switch coil 436 of stepping switch I so that stepping and counting will not occur after the interruption of the preselected programming of the duplicating cycle in a similar manner as previously described with respect to the use of the overfeed tray 506. This switch arrangement is identified in FIGURE 3 as having two positions, one being "continuous" and the other "count." The "continuous" position being the position wherein switch 435 is open and the "count" position being the position wherein switch 435 is closed. The operator may therefore run any desired number of additional copies at any point of the duplicating cycle by throwing switch 435 to the "continuous" position or open position until the desired number of copies have been duplicated and still have the benefit of the preselected programming.

When the operator has duplicated a sufficient number of copies switch 435 is set to position "count" which closes the path between the sheet detector contact 201 and the stepping coil 436 of stepping switch I thus resuming the preset duplicating program.

TERMINATION OF DUPLICATING CYCLE AT ANY POINT IN THE DUPLICATING CYCLE AND ADVANCEMENT TO THE POST-PRINTING OPERATION

By connecting the push button start switch 128 to the homing relay 220 through contact 414 of stepping switch IV, the start button will assume an additional function of being able to terminate the duplicating operation which

is in progress at any time subsequent to the stepping of stepping switch IV from its home position and advance the program immediately to the post-printing operation.

When the start button 128 is pressed during, for example, the pre-printing cycle, contact 414 is closed and wipers 409, 410, 411, 412 and 501 of stepping switch I are homed to position 430, from ground, push button start switch 128, through contact 414, wiper 501 of stepping switch IV and further through the bussed contacts of stepping switch IV associated with wiper 501, interrupter contact 187 and coil 100 of stepping switch IV to minus 90 volts. In this position, the homing relay 220 is energized from ground, push button start switch 128, contact 414 of stepping switch IV, wiper 501 of contact 430, and through coil 220 to minus 90 volts. After the energization of relay 220 the post printing cycle is immediately called into operation as previously stated. After stepping switch IV has been initially stepped, the operator is thereby capable of terminating the printing cycle at any time and may advance the duplicating program to the post-printing operation.

By pressing the start button 128, the operator will instruct the duplicator to consider the sheet of paper being fed as the last sheet to be duplicated and will automatically cut in the post-printing program. This is particularly useful where the operator desires to halt the machine by pressing the start button 128 at any time after the duplicator has been started.

As an emergency control device the operator can press the start button 128 when the emerging copy is unacceptable and thereby clean up the lithographic masters and the blanket roll for the next run or a re-run.

INK RUNDOWN SELECTION AND OPERATION

A lithographic master with very little ink image present on its surface is more suitable for subsequent handling, such as making additional entries onto the master and the like as well as being cleaner to handle. Therefore, if it is desired to have ink rundown, that is, where the ink image is partially removed from the lithographic masters by inhibiting the application of ink to the lithographic masters during the running of the last several copies of copy paper through the duplicator, the appropriate dial switches 458, 459 and 460 are manipulated.

Switches 460, 459 and 458 are provided to control the point in the duplicating cycle at which ink will no longer be applied to the lithographic master. Switches 460, 459 and 458, respectively, control the units, ten and hundreds settings as seen in FIGURE 3. For example, if the operator has set up "377" copies to be duplicated and it is desired that the last four copies of the "377" copies be duplicated are to be run without the ink system functioning, the operator dials "3" on dial switch 460, "7" on dial switch 456, and "3" on dial switch 497. When the 373rd sheet of copy paper is sensed by the sheet detector contact 201, a signal is sent to the stepping switch I from ground, contact 201, contact 441 of relay 500, switch 435, contact 433 of relay 130, and to coil 436 of stepping switch I to minus 90 volts thereby advancing wiper 438 of stepping switch I to the preselected position "3" on switch 460. At this time, wiper 445 of stepping switch II is at the "7" position contacting dial switch 459 and wiper 455 of stepping switch III is at the "3" position contacting dial switch 458. Thus a circuit is completed from ground, through wiper 438 of stepping switch I, position "3" of switch 460, switch 460 to wiper 445 of stepping switch II, position "7" of switch 459, switch 459 to wiper 455 of stepping switch III, position "3" of switch 458, switch 458 to the coil of relay 494 to minus 90 volts. Ink stop relay 494 is thereby energized opening contact 429 of relay 494, de-energizing ink relay 150 and thus stopping all ink functions. The paper feed system will still continue to feed the additional four copies called for by the copy count program preselected by the operator until the 377th copy is processed through

the duplicator. It should be remembered that the copies are fed into the duplicator with the ink system not functioning, which means that as each blank sheet of paper contacts the blanket roll 13 it will indirectly deplete the existing ink image on the lithographic master.

The foregoing ink rundown program automatically provides for the cessation of the functioning of the ink system at a predetermined number of copies before the final copy is duplicated. This means that the copies duplicated last will have successingly less ink imprinted thereon.

AUTOMATIC CONTROL OF THE POST PRINTING OPERATIONS ACCORDING TO THIS INVENTION

Ejection of the Lithographic Masters

After the last copy has run through the duplicator the lithographic masters are ejected from the plate segment of the main cylinder 14 and delivered into a receiving tray (not shown).

Referring to FIGURE 7, stepping coil 472 of stepping switch V is energized and caused to step one position when homing relay 220 is energized through the stepping switches I, II and III as previously explained. Stepping coil 472 of stepping switch V is energized from ground through wiper 437 of stepping switch I and through the stepping switches I, II and III and the dial switches 495, 496 and 497 as described with reference to the energization of relay 220 and the same path to ground is extended from dial switch 497 to contact position 476 of stepping switch V as is extended to relay coil 220 and further the path is extended through wiper 470 and the interrupter contact 471 of stepping switch V and the coil 472 to minus 90 volts. Stepping switch V thereby steps one position and the circuit path from ground, above described, to stepping coil 472 of stepping switch V is opened as can be readily seen in FIGURE 7 inasmuch as wiper 470 steps from its home position 476.

Referring to FIGURES 5, 6a, 7, 9, 15 and 16, relay 400 is energized in response to the stepping of stepping switch V, from ground through wiper 409 of stepping switch IV, through closed switch 502, wiper 475 and contact 479 of stepping switch V to the coil of relay 400 and minus 90 volts. Relay 400 is thereafter energized from ground through normally closed push button 401 and contact 480 of relay 400. Clamp electro-magnets 527 and 528 are thereby energized from ground through contacts 481 and 482, respectively, of relay 400. Clamp electro-magnets 527 and 538 as can be seen in FIGURE 15 control cams 524 and 523 which in turn open and close jaws 518 and 517 of jaw clamps 521 and 520, respectively. When jaw 518 of jaw clamp 521 is open, the overlay or secondary lithographic master will be lifted from its position much in the same fashion as a printed copy so that it will be fed into the ejection system and into the receiving tray (not shown). Similarly, when jaw 517 of jaw clamp 520 is open the primary lithographic master is ejected and delivered to the receiving tray (not shown).

The cams 524 and 523 are pivotally moved into their operative position by the energization of clamp electro-magnets 527 and 528 which overcome the biasing force of springs 529 and 530 thereby aligning cams 524 and 523 with the lifting arms 534 and 533. As previously explained, the biasing springs 529 and 530 pivotally urge the cams 524 and 523 out of the path of the lifting arms 534 and 533 when clamp electro-magnets 527 and 528 are de-energized so that subsequent rotations of the main cylinder 14 causes the lifting arms 534 and 533 to contact cams 524 and 523.

PROTECTION OF THE LITHOGRAPHIC MASTERS

This automatic ejection of the lithographic masters from the plate segment into the receiving tray makes the lithographic masters available for further handling or processing. Quite often the lithographic masters will require filing for future re-runs. However, the litho-

graphic masters or master has moisture and moist ink on its surface resulting in the possibility of smudging on the first copy of the next run and the probability of staining the operator's hands. It is, therefore, desirable that the lithographic master surface be protected so that the moist ink does not spread or stain the person handling the lithographic master. An additional sheet of copy paper is delivered to the receiving tray, which serves to protect the surface of the lithographic master, thereby keeping the image intact and enabling handling without unnecessary smudging of the operator's hands.

After the ejection of the lithographic master from the main cylinder 14 and its subsequent delivery to the receiving tray, the next revolution of the main cylinder 14 of the duplicator advances the wipers 470, 473, 474 and 475 of stepping switch V to position 485. Switch V is sequentially stepped with each revolution to the main cylinder 14 after the initial stepping of stepping switch V as described. Stepping switch V is energized from ground through wiper 409 of stepping switch IV and contact 430 of stepping switch IV, contacts 413 of relay 220 which are closed at this time, contacts 110 which are closed once each revolution of main cylinder 14 by cam 111 attached thereto, closed contacts 478 of stepping switch V and the step-coil 472 to minus 90 volts. The paper feed electro-magnet 91 is activated through a path from ground, through wiper 409 and contact 430 of stepping switch IV, closed switch 502, wiper 475 and contact 485 of stepping switch V, switch 432, and the paper feed electro-magnet 91 to minus 90 volts thereby causing one more sheet of paper to be fed through the duplicator. The feeding of this sheet of paper will not result in the blank sheet of paper being acted upon by the printing instrumentalities. The blank sheet of paper merely passes through the duplicator and is deposited into the receiving tray serving only as a protective sheet overlaying the possibly wet lithographic master.

CLEAN-UP OF THE BLANKET ROLL

40 The blanket roll 13 retains the residual ink image from the duplicating run. This residual ink image must be removed from the blanket roll 13 prior to the commencement of the next duplicating cycle. In the past, this required the operator to manually remove the ink image 45 from the blanket roll 13 and usually by wiping the surface of the blanket roll 13 with a solvent soaked cloth. When stepping switch V has stepped to position 485 as described, current also flows from ground through wiper 409 and contacts 430 of stepping switch IV, through contact 413 of relay 220, through wiper 474 and contact 485 of stepping switch V through the coil of relay 486 to minus 90 volts thereby energizing blanket roll wash relay 486. Relay 486 is thereafter energized from ground, through wiper 409 and contact 430 of stepping switch IV, contact 413 of homing relay 220 which is closed at this time due to the de-energization of relay 220, and contact 487 of relay 486. When relay 486 is energized, contact 425 of relay 486 is opened and contact 426 of relay 486 is closed. In response to the closing of contacts 426 of relay 486, the blanket wash electro-magnet 488 shown in FIGURES 6b and 13 is energized and the water feed electromagnet 31 is de-energized.

Referring to FIGURES 13 and 14, energization of the electro-magnet or solenoid 488 enables air to flow from a source (not shown) into piston 536 thereby causing blanket roll wash rollers 541 and 542 to move arcuately in a clockwise direction to contact the surface of blanket roll 13. The blanket roll wash roller assembly including rollers 541 and 542 is pivotally mounted on shaft 540 secured to the duplicator in any convenient manner and is urged in a clockwise direction as seen in FIGURES 13 and 14 by the activation of the connecting link 537 attached to the piston of air cylinder 536.

After the blanket roll wash roller assembly including rollers 541 and 542 is rotated into contact with blanket

roll 13, ink is removed from the blanket roll 13 as explained hereinafter. Rollers 541 and 542 are rotated by the frictional force delivered to them from the blanket roll 13. An ink solvent is carried in the reservoir 543 into which roller 542 is partially immersed. The contact rotation of the rollers 541 and 542 and the blanket roll 13 causes the solvent from reservoir 543 to be transferred from the reservoir 543 to the roller 542 and thence to roller 541 and finally to the surface of the blanket roll 13. The solvent picks up ink deposited on the blanket roll 13 and carries the dissolved ink back onto roller 541 and thence the roller 542 back to reservoir 543. As the blanket roll 13 is washed, wipers 470, 473, 474 and 475 of stepping switch V are caused to step one step with each revolution of the main cylinder 14 of the duplicator as a result of the opening and closing of contact 110, as previously described. Stepping switch V continues to step until wiper 470 thereof reaches the dial setting of the blanket roll wash switch 492 which is set for a predetermined number of blanket roll wash revolutions. Thereafter the blanket wash relay 486 is de-energized as will be seen clearly hereinafter.

Contacts 426 of relay 486 opens thereby de-energizing blanket wash solenoid 488, thereby, removing the pressure from the air piston 536 causing the oscillating roller assembly including rollers 541 and 542 to be arcuately urged in a counterclockwise position as viewed in FIGURES 13 and 14 by the action of the biasing spring 538.

After the blanket roll 13 is washed a waiting period is ordinarily required before the duplicator may be again utilized. This waiting period is necessary to insure that the solvent has completely evaporated from the blanket roll surface for apparent reasons. The rate of evaporation of the solvent will be dependent upon the nature of the solvent, and the temperature and humidity conditions.

AIR DRYING OF THE BLANKET ROLL

Referring to FIGURE 10, there is shown an air-blow tube 491 mounted parallel to the shaft of the blanket roll 13 and placed in cooperative association with the blanket roll 13. The air-blow tube 491 is equipped with a plurality of small circular apertures 544 drilled into the surface of the air-blow tube 491 lying on a center line parallel to the center line of the air-blow tube 491.

When wiper 473 of stepping switch V has been advanced due to the opening and closing of contact 110 as previously described, to the position at which air dry switch 489, as seen in FIGURES 3 and 7, is set, current flows from ground, through wiper 473 of stepping switch V, air dry switch 489, and coil 490 of air solenoid valve 490 to minus 90 volts. The air dry solenoid 490 is thereby energized enabling a stream of air to pass through air solenoid valve 490 from an air source (not shown) to the air-blow tube 491 and thence out apertures 544 in the surface of the air-blow tube 491. The resulting air stream impinges on the surface of the blanket roll 13 causing the applied solvent to readily evaporate.

SIMULTANEOUS REMOVAL OF INK FROM THE BLANKET ROLL AND THE SURFACE OF THE LITHOGRAPHIC MASTERS

In order to conserve paper and time and to avoid the use of the ink rundown procedure previously described, ink may be removed from the lithographic masters at the same time that ink is removed from the blanket roll 13. This may be accomplished by the use of switch 502 indicated in FIGURE 3 as the "Mat Wash" switch. During the blanket roll 13 clean-up cycle, as previously stated, a solvent is applied to the surface of the blanket roll 13 from a solvent reservoir associated with a blanket roll wash roller assembly. The ink is dissolved in the solvent and fed back into the solvent reservoir. During the clean-up cycle, the blanket roll electro-magnetic latch 71 is rendered inoperative as a result of the de-energization of

blanket roll relay 170 due to the opening of contact 222 of homing relay 220.

Referring to FIGURE 6a, it will be seen that switch 502 is provided so that the blanket roll electro-magnetic latch 71 may be energized through switch 502. Normally, relay 170 activates the electro-magnetic latch 71 from ground, through contact 171 of relay 170 and through electro-magnet 71 to minus 90 volts causing the blanket roll 13 to contact the lithographic master as the duplicator rotates. Therefore, if switch 502 is switched to its "on" position as viewed in FIGURE 3, which is the position wherein switch 502 is connected to contact 171 of relay 170 as viewed in FIGURE 6a, preceding the blanket roll clean-up cycle, the solvent applied to the blanket roll 13 is also applied to the lithographic masters, whereupon the ink on the lithographic master is transferred to the solvent layer on the blanket roll and thence back into the solvent reservoir.

The switching of switch 502 to its "on" position before the initiation of the blanket roll clean-up cycle prevents the energization of relay 400 and hence the ejection of the lithographic masters. When switch 502 is in its "on" position ground is removed from wiper 475 of stepping switch V and, as can be readily understood, neither relay 400 nor the paper feed electro-magnet 91 are energized through stepping switch V. Therefore, the lithographic masters remain clamped to the main cylinder 14 and no extra blank sheet of copy paper is delivered to the receiving tray as aforescribed. Further the blanket roll electro-magnet 71 is energized from ground, wiper 409 and contact 430 of stepping switch IV, switch 502, and to the electro-magnet 71 to minus 90 volts. Therefore the lithographic masters will contact the blanket roll 13 during the blanket roll clean-up cycle and ink will be removed by the solvent action described with relation to the cleaning of the blanket roll 13.

The blanket wash mechanism continues to operate due to the continued rotation of the duplicator, and the consequent opening and closing of the switch 110 as previously described. Stepping switch V and consequently wiper 470 is stepped each time cam 111 reaches the point at which the operator has preset the blanket wash dial 492, at which point the blanket wash operation will stop, as will be seen hereinafter.

When wiper 470 of stepping switch V has advanced to the pre-set position of blanket wash dial switch 492, a circuit path is completed from ground through wiper 409 and contact 430 of stepping switch IV, contact 413 of relay 220, blanket wash switch 492, wiper 470, interrupter contact 471 and stepping coil 472 of stepping switch V to minus 90 volts. The energization of stepping coil 472 over this path causes wipers 470, 473, 474 and 475 of stepping switch V to step to their home position 476. At this position and as previously stated contact 415 of stepping switch V is closed and contact 478 of stepping switch V is opened by the action of cam 477 associated with stepping switch V. During the next revolution of the duplicator, cam 111 closes contact 110 and a pulse is transmitted from ground, through wiper 409 and contact 430 of stepping switch IV, contact 413 of relay 220, contact 110, contact 415 of stepping switch V, contact 416 of relay 190 to stepping coil 100 of stepping switch IV to minus 90 volts. Activation of stepping coil 100 results in the wipers 409, 410, 411, 412 and 501 of stepping switch IV stepping to their home position at position 493.

Inasmuch as ground is not presented at position 493 of stepping switch IV, the blanket wash relay 486 becomes deenergized as does the power to contact 110, thus preventing further pulses from emanating from contact 110.

The advancement of wiper 410 of stepping switch IV to the home position 493 of stepping switch IV also removes ground from the circuit to the water relay 130 causing the deenergization of water relay 130 thereby stopping all moisture system functions.

Finally, with the wipers of stepping switch IV in their

home position at 493, the motor relay 120 becomes de-energized, turning off the motor 129 and hence causing the cessation of rotation of the main cylinder 14.

Briefly reviewing the automatic programming that has been accomplished in the "Post Printing" phase of the duplicating cycle, it has been shown that the operator need handle only inked lithographic masters having a minimum of residual ink thereon. The lithographic master, after it has been completely acted upon by the various devices of the duplicator may be ejected into a receiving tray and, to further protect it, an additional sheet of blank paper is fed through the duplicator to overlay the moist lithographic master. Further, the residual ink image remaining on the rubber blanket roll is automatically exposed to a cleaning device employing a solvent which washes the ink image from the blanket roll. The removal of the solvent from the blanket roll is facilitated by the automatic provision of a stream of air blown against the surface of the blanket roll.

OPERATION

Typical Requirements of an Offset Lithographic Duplicating Cycle

In order to facilitate the understanding of the aforedescribed duplicator the operation of such a duplicator will be hereinafter described for various conditions of use.

Assume that the lithographic duplicating medium is to be a direct image mat and an overlay mat. The direct image mat is a lithographic master which has been suitably imaged with primary data. The overlay mat is a similar master which contains variable data and overlays only a portion of the primary master data giving a composite image.

The following information has been supplied to the operator from a qualified source.

(1) The lithographic masters are to receive a premoistening treatment of four revolutions of the duplicator.

(2) A total of "377" copies are to be duplicated.

(3) During the duplicating run, it will be necessary to overfeed from the feed tray, a number of copies of smaller address label stock.

(4) The lithographic master is to have an ink rundown of four revolutions of the duplicator prior to being removed.

(5) The lithographic master is to have a protective sheet available upon removal from the receiving tray.

(6) The blanket is to be automatically washed prior to the next duplicating cycle.

(7) The blanket is to be in a condition of complete dryness and free of solvent immediately after the duplicating run and ready for the next duplicating cycle.

A primary lithographic master and a secondary lithographic master suitably imaged are delivered in a completely untreated manner to the offset duplicator operator.

OPERATOR MANIPULATIONS

The operator first throws the power switch 125 in lines L-1 and L-2 thereby connecting the 120 volt A.C. source to rectifier 127. Rectifier 127 thereafter supplies 90 volts to the various relays and coils.

The operator pre-sets the various dial switches in accordance with the prescribed program outlined earlier. Referring to FIGURE 3 of the drawing, dial switches 497, 496 and 495 are set to position "300," position "70," and position "7," respectively, to yield a count of "377."

To provide an ink rundown of four copies, the dial switches 458, 459 and 460 are set to position "300," position "70" and position "3," respectively.

Still referring to FIGURE 3 and proceeding to the bottom bank of dials, it will be seen that dial 417 determines the number of revolutions the duplicator makes during the period in which the pre-moistening mechanism 402 contacts the lithographic surface. Therefore, in accordance with the prescribed program, the operator will set the pointer on this dial to "4."

Dial 117 determines the number of revolutions the duplicator will make, while the moisture system is contacting the surface of the lithographic master prior to the activation of the ink system. The operator will set dial 117 to numeral "3"; which will result in the moisture system first contacting the lithographic master for four revolutions, at the conclusion of which the ink system will be activated.

Dial 118 is set at numeral "4" thereby rendering the blanket roll operative one revolution after the commencement of the feeding of the ink.

Dial 119 is set at numeral "7" thereby allowing ink to build up in the image areas on the lithographic master and be transferred to the blanket roll, resulting in a build-up of a printing image on the blanket roll for three revolutions of the duplicator, at which time the paper feed will commence.

The foregoing settings will permit the first copy to have an image of a proper density.

20 Switch 492 will be set at numeral "5" by the operator, thereby allowing five revolutions of the duplicator during which the blanket wash device will act upon the blanket.

Switch 489 is set at numeral "3" thereby activating the 25 air dry mechanism after two revolutions of the duplicator which continues until the conclusion of the blanket wash cycle.

Assume that the primary lithographic master jaw clamp 520 and the secondary lithographic master jaw clamp 521 are in their open position as previously described which is the normal condition. The primary lithographic master and the secondary lithographic master are inserted into the jaw clamps 520 and 521, respectively, and push button 401 is activated. In response to the activation of push button 401 relay 400, if energized at this time, is de-energized which in turn de-activates electromagnets 527 and 528. Thereafter jaw clamps 520 and 521 are closed as previously described.

The operator thereafter moves etch handle 403 shown 40 in FIGURE 12 in a clockwise direction until the pawl 407 mounted on shaft 404 engages the latch 406. In this position, the applicator 408 contacts the surface of the lithographic master. The operator then depresses the start button 128 thereby commencing the program which has been preselected by the dial settings. It should be noted that push button 128 has been conveniently mounted in the handle 403 but it is contemplated that it can be mounted for safety reasons in more remote locations such as the control panel of FIGURE 3.

50 Stepping switch coil 100 of stepping switch IV is energized in response to the activation of push button switch 128 as previously described. When the operator releases push button switch 128, the wipers 409, 410, 411, 412 and 501 of stepping switch IV advance one step.

55 Wiper 409 energizes the motor relay 120 as described thereby closing contact 121 of relay 120. In response to the closing of contact 121 of relay 120 motor 129 is energized thereby causing the main cylinder 14 of the duplicator to rotate.

60 The pre-moistening mechanism 402 thereafter deposits moisture on the lithographic duplicating masters. Wipers 409, 410, 411, 412 and 501 of stepping switch IV are then advanced one step for each revolution of the duplicator due to the opening and closing of contact 110 by cam 111 as previously described. Wiper 412 of stepping switch IV is then advanced, along with wipers 409, 410, 411 and 502 of stepping switch IV to the preselected point at which the pre-moistening or etch switch 417 has been set which in this example is the fourth revolution 65 of the duplicator. Thereafter the wipers of the stepping switch IV home to position 418 of stepping switch IV as previously described. When stepping switch IV arrives at position 418 electro-magnet 420 is energized through relay 419 as described and interponent 422 is moved into the path of the cam follower arm 424. On the next revolution

75 the wipers of the stepping switch IV are advanced to the position 418 of stepping switch IV as previously described.

lution of the main cylinder 14, cam follower 424 pushes interponent 422 thereby pushing latch 406 out of engagement with pawl 407 of the pre-moistening mechanism 402 allowing the pre-moistening mechanism 402 to move in its inoperative position as described.

At the conclusion of the pre-moistening cycle of the duplicator and after stepping switch IV has homed to position 418, the water relay 130 is energized through wiper 410 of stepping switch IV as described. At this time the printing phase of the duplicating cycle commences. The water relay 130 remains energized through the succeeding steps of stepping switch IV through wiper 410 of stepping switch IV.

Ink relay 150 is also energized when stepping switch IV reaches position 418 as described and the ink electro-magnet 51 is thereafter energized from ground through contact 192 of relay 190.

Both moisture and ink are thereafter applied to the surface of the lithographic master as the main cylinder 14 of the duplicator rotates as previously described and stepping switch IV steps one step for each rotation of the main cylinder 14 as described until wiper 411 of stepping switch IV engages the pre-set position of the blanket roll switch 118 which is in this case position four and thereafter blanket roll relay 170 becomes energized as described and blanket roll electro-magnet 171 is energized as described and the blanket roll 13 is thereafter moved into engagement with the lithographic masters. Relay 170 is thereafter energized through contact 222 of relay 220 and contact 172 of relay 170.

Moisture and ink are then applied to the surface of the lithographic master as stepping switch IV continues to step with each revolution of the main cylinder 14 as described until wiper 412 of the stepping switch IV contacts the position at which the paper feed switch 119 is set which in this example is position seven and thereafter the paper feed relay 190 is energized as described.

When paper feed relay 190 is energized, the paper feed electro-magnet 91 is energized as described and paper commences to be fed to the duplicator.

If the ejector rake 519 as shown in FIGURES 17a and 17b is improperly positioned, contact 432 is opened as described and paper feed does not occur. The operator must thereafter move the ejector rake into its proper position to permit commencement of the paper feed.

The counting of copies is controlled by the sheet detector contact 201 closing and opening each time a blank sheet is fed into the feed roll assembly of the duplicator and counting proceeds as described.

In order to feed the required narrow paper stock during the printing cycle the operator places the special overfeed tray 505 as seen in FIGURE 12 containing the desired count of narrow stock, in position on the paper feed tray 522 as described.

The paper sensing element 509 shown in FIGURE 12 is thereafter moved to its raised position closing contact 499 thereby energizing relay 500. Relay 500 energizes the solenoid valve 511 as described. Solenoid valve 511 cuts off the vacuum to the suction foot 525. Inasmuch as narrow paper stock is overfed only one of the suction feet is required.

Upon completion of the feeding of the narrow paper stock from the overfeed tray, contact 499 is opened as described. Relay 500 is thereby de-energized de-energizing solenoid 511 thereby restoring vacuum to both suction feet. The printing operation is then resumed.

In order to perform the required ink rundown operation the transfer of ink from the ink form roller to the lithographic master is stopped after "373" copies have been duplicated. When the wipers on stepping switches I, II and III attain their preselected positions of the respective switches which are positions "3," "7" and "3," respectively, relay 494 is energized as described, opening contact 429 of relay 494 thereby de-energizing the ink

relay 150 stopping all ink functions at the preselected ink rundown position.

After the preselected total of "377" copies have been fed into the receiving tray the homing relay 220 is energized and terminates the operation of the various printing instrumentalities as described. Thereafter the lithographic master is ejected into the receiving tray as described.

The lithographic master, although it has been depleted of excess ink is not completely dry and will tend to smear and stain the operator in subsequent handling. Therefore, one additional sheet of blank paper is fed through the duplicator into the receiving tray to serve as a protective overlay as previously described.

15 The next portion of the programming calls for the clean-up cycle to commence. As previously described, stepping coil 472 of stepping switch V is initially energized when relay 220 is energized thereby stepping stepping switch V to position 479. Thereafter the opening and 20 closing of contact 110 with each revolution of the duplicator energizes and de-energizes stepping coil 472 as described thereby advancing wipers 470, 473, 474 and 475 of stepping switch V one step for each revolution of the duplicator as described. The blanket wash mechanism is 25 activated when wiper 474 of stepping switch V is stepped to position 485 where relay 486 is energized as described and the blanket wash mechanism is caused to contact the blanket roll 13 applying the solvent thereto for the duration of the number of cycles preselected by the operator 30 in setting up the program which in this example is five revolutions of the duplicator.

During the blanket wash operation, a quantity of solvent is supplied to the blanket roll 13 as previously described in order to effectively remove the ink image from the 35 blanket roll 13. The air stream from the air drying mechanism is applied to the blanket roll for three revolutions of the duplicator as determined by the setting of the air dry switch 409 as seen in FIGURE 3. When wiper 473 of stepping switch V has advanced to the contact 40 at which the air dry switch 489 is set, which, in this example, is numeral three, air solenoid 490 as viewed in FIGURE 10 opens thereby directing an air stream onto the surface of the blanket roll 13 facilitating the evaporation of the solvent from the blanket roll 13. The blanket 45 roll 13 is thereby in an ink free condition preparatory to the next duplicating cycle.

At the end of the blanket wash cycle, wipers 470, 473, 474 and 475 of stepping switch V are homed to position 476 as previously described. When stepping switch V 50 is in its home position 476, contact 415 of stepping switch V is closed and contact 478 is opened by the action of cam 477 associated with stepping switch V as described. The contact 110 causes a pulse to be sent to coil 100 as described which results in the stepping of wipers 409, 55 410, 411, 412 and 501 of stepping switch IV to their home position 493.

Thereafter motor relay 120 is de-energized as described thereby turning off motor 129.

At the same time and as previously described the 60 blanket wash relay 486 and the water relay 130 are de-energized thereby preventing further pulses from emanating from contact 110.

As described the duplicator will stop with the jaw clamps 520 and 521 open and in such a position as to be 65 readily accessible to the operator. The succeeding lithographic masters may then be readily inserted into the jaw clamps 520 and 521. The duplicator is now in condition for the commencement of the next duplicating cycle.

70 CONTINUOUS RUN OPERATION OF THE AUTOMATED OFFSET DUPLICATOR

If at the initiation of a duplicating cycle the continuous run switch 435 is thrown to the "continuous" position as illustrated in FIGURE 3, the energizing circuit from

sheet detector contact 201 to the stepping coil 436 of stepping switch I is interrupted as previously described. The count recording device comprising stepping switches I, II and III is thereby rendered inoperative and stepping of the stepping switches I, II and III does not occur after paper is fed to the duplicator.

The operator sets the copy selection units dial 495 on numeral "1" or any setting not "0" and the other copy selection dials 496 and 497 at "0" inasmuch as relay 220 would be energized if dial switches 495, 496 and 497 are set to "0" as can be seen in FIGURE 8. Next, switch 435 is thrown to the "continuous" position. The remainder of the dial switches may be set up as in the first described operation. The operator commences the operation of the duplicating cycle by moving 15 the pre-moistening mechanism 402 into operative position and then depressing push button start switch 128.

The pre-printing cycle and the printing cycle proceeds as previously described with the exception of the activation of the copy count mechanism comprising the stepping switches I, II and III. The printing phase continues until the operator again presses start push button 128. The activation of push button 128 energizes homing relay 220, through contact 414, wiper 501 and contact 430 to coil 220 and minus 90 volts, which causes the stopping of moisture, ink, blanket and paper feed functions, and the post feeding program is now ready to begin, all as described previously.

If an ink rundown is desired, the dial 495 should be set at a setting which exceeds the number of ink rundown copies required on this particular program and the ink rundown dial 460 should be set at a lower number. Thus, when the operator has duplicated the number of copies desired and has pressed start push button switch 128, the last few copies as determined by the setting of dial switches 495 and 460 are duplicated without being applied to the lithographic master. The inked image on the lithographic masters and the blanket roll 13 is then depleted by the run through of the subsequent copies.

AUTOMATIC CLEAN-UP OF MASTER AND BLANKET

It is often required that the lithographic master be thoroughly cleaned so that additional information may be added to the master initial duplicating run. Such a lithographic master must be dry, and have all excess ink removed before it may be altered by a typewriter or other methods of imparting an image to the surface of the lithographic master.

Switch 502 as seen in FIGURES 3 and 6a controls the operation of the electro-magnetic latch 71 which renders the blanket roll operative.

Therefore, if operator closes switch 502 before the last required copy has been fed through the duplicator and the blanket roll clean-up cycle has begun the ejection system will be rendered inoperative as described and the lithographic masters remain clamped on the plate segment of the main cylinder 14.

The programming will automatically continue and proceed into the post printing phase where the blanket roll wash rollers are caused to act upon the blanket roll, applying a layer of solvent to its surface. By closing switch 502, the electro-magnetic latch 71, which operates the blanket roll 13 keeps the blanket roll 13 in contact with the surface of the lithographic masters so that solvent is simultaneously applied to the blanket roll surface and the surface of the lithographic masters. The surface of the lithographic masters will receive an application of solvent as determined by the dial setting of dial switch 492 and the air drying as previously described will begin as determined by the setting of dial switch 489.

In the drawings and specification, there has been set forth a preferred embodiment of the invention and although specific terms are employed, these are used in a generic and descriptive sense only, and not for purposes

of limitation. Changes in form and the proportion of parts, as well as the substitution of equivalents are contemplated. Specifically and by way of example, it is contemplated that a mechanical system of cams and gears can be substituted for the electrical system including the stepping switches and electro-magnets performing the control operations and that electronic counters may be substituted for the switches. It is meant to cover in the appended claims these and other modifications, changes and variations as fall within the true spirit and scope of the invention.

What is claimed is:

1. In an offset duplicating machine including a main cylinder and a blanket roll operative in a throw-in position engaging said main cylinder and a paper feed mechanism operative between a normal condition and an operative condition, a count means functioning in timed relation to the main cylinder, first switch means for recording the count from said count means, paper feed control means responsive to a preselected count recorded in said first switch means for operating said paper feed mechanism into said operative condition, a first restoring means responsive to a preselected count recorded in said first switch means greater than said paper feed pre-selected count for operating said paper feed mechanism to said normal condition, the combination comprising: a second switch means for recording the count from said count means, switch control means responsive to a pre-selected count recorded in said first switch means greater than said first restoring means preselected count for transferring the recording of the count from said first switch means to said second switch means, a blanket roll clean-up mechanism operative between a normal position and an operative position, blanket roll clean-up mechanism control means responsive to a preselected count recorded in said second switch means for operating said blanket roll clean-up mechanism into said operative position, and second restoring means responsive to a preselected count recorded in said second switch means greater than said blanket roll clean-up mechanism preselected count for sequentially restoring said second switch means and operating said blanket roll clean-up mechanism into said normal position and restoring said first switch means.

2. The combination in an offset duplicating machine as set forth in claim 1, further including blanket roll control means for operating said blanket roll from said throw-in position to a normal position disengaging said main cylinder, said blanket roll control means being operated by said first restoring means conjointly with the operation of said paper feed mechanism to said normal condition.

3. In an offset duplicating machine including a main cylinder and provided with a blanket roll operative between a normal position and a throw-in position and a paper feed mechanism operative between a normal condition and an operative condition, count means functioning in timed relation to the main cylinder, first switch means for recording the count from said count means, blanket roll control means responsive to a preselected count recorded in said first switch means for operating said blanket roll into said throw-in position, paper feed control means responsive to a preselected count recorded in said first switch means greater than said blanket roll preselected count for operating said paper feed mechanism into said operative condition, a first restoring means responsive to a preselected count recorded in said first switch means for restoring said paper feed mechanism to said normal condition, the combination comprising: a second switch means for recording the count from said count means, switch control means responsive to a pre-selected count recorded in said first switch means greater than said first restoring means preselected count for transferring the recording of the count from said first switch means to said second switch means, a blanket roll clean-up mechanism operative between a normal posi-

tion and a throw-in position, blanket roll clean-up control means responsive to a preselected count recorded in said second switch means for operating said blanket roll clean-up mechanism into said operative position, an air dry mechanism for providing a plurality of streams of air to said blanket roll operative between a normal position and an operative position, air dry control means responsive to a preselected count recorded in said second switch means greater than said blanket roll clean-up preselected count for operating said air dry mechanism into said operative condition, and second restoring means responsive to a preselected count recorded in said second switch means greater than said blanket roll clean-up mechanism preselected count for sequentially restoring said second switch means and operating said blanket roll and said blanket roll clean-up mechanism and said air dry mechanism to said normal positions and restoring said first switch means.

4. In an offset duplicating machine including a main cylinder and provided with a moisture applying mechanism and an ink applying mechanism each operative between a normal position and an operative position, a blanket roll operative between a normal position and a throw-in position, a paper feed mechanism operative between a normal condition and an operative condition, count means functioning in timed relation to the main cylinder, a first switch means having a normal position and an operative position for recording the count from said count means, moisture applying mechanism control means responsive to a preselected count recorded in said first switch means for operating said moisture applying mechanism into said operative position, ink applying mechanism control means responsive to a preselected count recorded in said first switch means for operating said ink applying mechanism into said operative position, blanket roll control means responsive to a preselected count recorded in said first means for operating said blanket roll into said throw-in position, paper feed control means responsive to a preselected count recorded in said first switch means greater than said blanket roll preselected count for operating said paper feed mechanism into said operative condition, first restoring means responsive to a preselected count recorded in said first switch means for restoring said moisture applying mechanism, said ink applying mechanism, and said blanket roll to their normal positions and for restoring said paper feed mechanism to said normal condition, the combination comprising: a second switch means for recording the counts from said count means, switch control means responsive to a preselected count recorded in said first switch means greater than said first restoring means preselected count for transferring the recording of the counts from said first switch means to said second switch means, a blanket roll clean-up mechanism operative between a normal position and an operative position in contact with said blanket roll, blanket roll clean-up mechanism control means responsive to a preselected count recorded in said second switch means for operating said blanket roll clean-up mechanism into its operative position, and second restoring means responsive to a preselected count recorded in said second switch means greater than said blanket roll clean-up mechanism preselected count for sequentially restoring said second switch means and operating said blanket roll clean-up mechanism to said normal position and restoring said first switch means.

5. In an offset duplicating machine including a main cylinder and provided with a blanket roll operative between a normal position and a throw-in position and a paper feed mechanism operative between a normal condition and an operative condition, count means functioning in timed relation to the main cylinder, first switch means for recording the count from said count means, blanket roll control means responsive to a preselected count recorded in said first switch means for operating said blanket roll into said throw-in position, paper feed

control means responsive to a preselected count recorded in said first switch means greater than said blanket roll preselected count for operating said paper feed mechanism into said operative condition, a first restoring means responsive to a preselected count recorded in said first switch greater than said paper feed preselected count means for restoring said blanket roll into said normal position and said paper feed mechanism to said normal condition; the combination comprising a second switch means for recording the count from said count device from said count means, switch control means responsive to a preselected count recorded in said first switch means greater than said first restoring means preselected count for transferring the recording of the count from said count means from said first switch means to said second switch means, a blanket clean-up mechanism operative between a normal position and an operative position, blanket clean-up control means responsive to a preselected count recorded in said second switch means for operating said blanket roll clean-up mechanism in said operative position, an air dry mechanism for providing a plurality of streams of air to said blanket roll operative between a normal condition and an operative condition, control means for said air dry mechanism responsive to a preselected count recorded in said second switch means greater than said blanket clean-up preselected count for operating said air dry mechanism into said operative condition, second restoring means responsive to a preselected count recorded in said second switch means greater than said blanket roll clean-up mechanism preselected count for sequentially restoring said second switch means and operating said blanket roll clean-up mechanism into said normal position and operating said air dry mechanism into said normal condition and restoring said first switch means.

6. In an offset duplicating machine including a main cylinder having thereon a lithographic master jaw clamp operative between an open position and a closed position, said lithographic master jaw clamp normally being operative into the closed position for securing a lithographic master to said main cylinder, a blanket roll operative in a throw-in position engaging said main cylinder, a paper feed mechanism operative between a normal condition and an operative condition, a count means functioning in timed relation to the main cylinder, a first switch means for recording the count from said count means, paper feed control means responsive to a preselected count recorded in said first switch means for operating said paper feed mechanism into said operative condition, a first restoring means responsive to a preselected count recorded in said first switch means greater than said paper feed preselected count for operating said paper feed mechanism to said normal condition, the combination comprising: a second switch means for recording the count from said count means, switch control means responsive to a preselected count recorded in said first switch means greater than said first restoring means preselected count for transferring the recording of the count from said first switch means to said second switch means, a lithographic master jaw clamp control means responsive to a preselected count recorded in said second switch means for operating said lithographic jaw clamp into said open position thereby releasing the retained lithographic master, a blanket roll clean-up mechanism operative between a normal position and an operative position, blanket roll clean-up mechanism control means responsive to a preselected count recorded in said second switch means greater than said lithographic jaw clamp control preselected count for operating said blanket roll clean-up mechanism into said operative condition, and a second restoring means responsive to a preselected count recorded in said second switch means greater than said blanket roll clean-up mechanism selected count for sequentially restoring said second switch means and operating said blanket roll

clean-up mechanism into said normal position and restoring said first switch means.

7. The offset-duplicating machine combination set forth in claim 6 wherein said main cylinder has attached thereto a rotatable camming surface and wherein said lithographic master jaw clamp control means includes a cam lever selectively engaging said camming surface for operating said jaw clamp into said open position and electromagnetic means controlled from said second switch for engaging said cam lever to said camming surface.

8. In an offset duplicating machine including a main cylinder having arranged thereon a plurality of lithographic master jaw clamps each operative between an open position and a closed position, manual means for operating said lithographic master jaw clamps into said closed positions for positioning lithographic masters and overlays on the main cylinder, a blanket roll operative in a throw-in position engaging said main cylinder, a paper feed mechanism operative between a normal condition and an operative condition, a count means functioning in timed relation to the main cylinder, first switch means for recording the count from said count means, paper feed control means responsive to a preselected count recorded in said first switch means for operating said paper feed mechanism into said operative condition, a first restoring means responsive to a preselected count recorded in said first switch means greater than said paper feed preselected count for operating said paper feed mechanism to said normal condition, the combination comprising: a second switch means for recording the count from said count means, switch control means responsive to a preselected count recorded in said first switch means greater than said first restoring means preselected count for transferring the recording of the count from said first switch means to said second switch means, lithographic master jaw clamp control means responsive to a preselected count recorded in said second switch means for sequentially operating said plurality of jaw clamps into said open positions thereby sequentially to release the overlays and lithographic masters in the order of stacking on the main cylinder, blanket roll clean-up mechanism operative between a normal position and an operative position, blanket roll clean-up mechanism control means responsive to a preselected count recorded in said second switch means greater than said lithographic jaw clamp preselected count for operating said blanket roll clean-up mechanism into said operative position, a second restoring means responsive to a preselected count recorded in said second switch means greater than said blanket roll clean-up mechanism preselected count for sequentially restoring said second switch means and operating said blanket roll clean-up mechanism into said normal position and restoring said first switch means.

9. In an offset duplicating machine including a main cylinder carrying thereon a lithographic master jaw clamp selectively operative in an open position and normally operative in a closed position for positioning a lithographic master on the main cylinder, the combination comprising lithographic master etch material applicator operative between a normal position and an operative position, a blanket roll operative between a normal position and a throw-in position, paper feed mechanism operative between a normal condition and an operative condition, manual means for operating said etch material applicator into said operative position, count means functioning in timed relation to the main cylinder, first switch means for recording the count from said count means, etch material applicator control means responsive to a preselected count recorded in said first switch means for operating said etch material applicator into said normal position, blanket roll control means responsive to a preselected count recorded in said first switch means greater than said etch material applicator preselected count for operating said blanket roll into said throw-in position, paper feed con-

trol means responsive to a preselected count recorded in said first switch means greater than said blanket roll preselected count for operating said paper feed mechanism into said operative condition, a first restoring means responsive to a preselected count recorded in said first switch means for restoring said feed mechanism to said normal condition, a second switch means for recording the count from said count means, a switch control means responsive to a preselected count recorded in said first switch means greater than said first restoring means preselected count for transferring the recording of the count from said first switch means to said second switch means, a blanket roll clean-up mechanism operative between a normal position and an operative position, a blanket roll clean-up mechanism control means responsive to a preselected count recorded in said second switch means for operating said blanket roll clean-up mechanism into said operative position, and second restoring means responsive to a preselected count recorded in said second switch means greater than said blanket roll clean-up mechanism preselected count for sequentially restoring said second switch means and operating said blanket roll clean-up mechanism into said normal position and restoring said first switch means.

10. In an offset duplicating machine including a main cylinder having positioned thereon a lithographic master, etch material applicator operative between a normal position spaced from said cylinder and an operative position contiguous said cylinder at said lithographic master, said etch material applicator comprising a moisture dispensing element for engaging said lithographic master in said operative position, a latching mechanism positioned adjacent said main cylinder for holding said etch material applicator in said operative position, biasing means operating against said latching mechanism to move said etch material applicator into said normal position, and an electro-magnet associated with said latching mechanism selectively operated to release said latching mechanism and cause said etch material applicator to be operated by said biasing means from said operative position to said normal position.

11. In an offset duplicating machine including the main cylinder and a paper feed tray for providing a paper supply thereto, a paper feed mechanism operative between a normal condition and an operative condition, count means functioning in timed relation to the main cylinder, switch means for recording the count from said count means, paper feed control means responsive to a preselected count recorded in said switch means for operating said paper feed mechanism into said operative condition and first restoring means responsive to a preselected count recorded in said switch means greater than said paper feed preselected count for restoring said paper feed mechanism to its normal condition, the combination further including an overfeed tray positioned in said paper feed tray, a count interrupting device responsive to the positioning of said overfeed tray in said paper feed tray for interrupting the recording of counts in said switch means, whereby the supply of paper in said overfeed tray is duplicated without recording a count and without destroying a recorded count in said switch means.

12. In an offset duplicating machine including a main cylinder and provided with a paper feed mechanism operative between a normal condition and an operative condition, count means functioning in timed relation to the main cylinder, a switch means, a plurality of control means each operative for carrying out a corresponding operational function of the duplicating machine under direction of said count means, said switch means being operative in a cycle from a home position for sequentially selecting said ones of said control means, said switch means further being operative through its cycle from said count means and being disassociated from said count means upon selection of one of said control means, whereby the cyclic operation of said switch means is inter-

rupted during the corresponding operational function, and system clearing means associated with said first switch means and selectively operable sending cyclic operation of said switch means continuous to home position thereby terminating any initiated operational functions and avoiding any uninitiated operational functions at said control means.
